ROTARY HOOK FOR SEWING MACHINES

Emil J. Billington, Chicago, Ill., assignor to Union Special Machine Company, Chicago, Ill., a corporation of Illinois

Application September 12, 1940, Serial No. 356,451

4 Claims. (Cl. 112—228)

This invention relates to rotary hooks useful in lock stitch sewing machines to cooperate with the needles in stitch formation.

In rotary hooks as ordinarily constructed, the non-rotating or bobbin housing component is restrained against rotation by a fixed engaging element with provision of sufficient looseness for clearance by the front limb of the needle thread loop as the latter sweeps across the face of the hook during each stitch-forming cycle; while the bobbin thread emerges through an egress opening at one side of the bobbin housing component and passes upward in contact with the face of the hook. As a consequence, owing to the loose play allowed the bobbin housing component, the latter is moved slightly in a direction opposite to that of the rotating or needle thread loop-seizing component during each stitch forming cycle under the pull of the bobbin thread as the work is progressed by the feed of the machine. A slapping action thus takes place between the usual projection on the fixed rotation-restraining element of the machine and one side of the usual interengaging notch formed between the cheek projections on the flange face at the top of the bobbin housing component. This slapping action is not only objectionable from the standpoint of the noise which it creates, especially when the sewing machine is operated at high speeds, but also in that it promotes rapid wear of the parts. Moreover, the usual forms of rotary hooks are so constructed that the front limb of the needle thread loop in its sweep across the face of the hook during the stitch forming cycle, is obliged to contact over a considerable length with the bobbin thread. As a result, the movement of the needle thread loop around the bobbin case holder is impeded and its release correspondingly delayed.

My invention has for its chief aim to overcome the foregoing drawbacks, which desideratum I attain in practice, as hereafter more fully disclosed, through structural changes in the hook, whereby, during each stitch-forming cycle, the loose play between the non-rotating or bobbin housing component and the fixed rotation-restraining element is effectively prevented, and through which the bobbin thread is controlled in such a manner as to obviate contact thereof with the outer limb of the needle thread loop as the latter sweeps across the face of the hook.

Other objects and attendant advantages will appear from the following detailed description of the attached drawing, wherein Fig. 1 is a fragmentary view in cross section, of a lock stitch sewing machine conveniently embodying my invention.

Fig. 2 is a view in top plan looking as indicated by the angled arrows II—II in Fig. 1; and Fig. 3 shows the bottom view of the rotation-

restraining element associated with my improved rotary hook.

With more detailed reference to the illustration, the numeral 10 designates the work support 5 of the sewing machine, which support has an aperture 11 for passage through it of a vertically reciprocating thread-carrying needle partially indicated at 12 in Fig. 1. The work support 10 also has slots 13 at opposite sides of the needle aperture 11 in the direction of feeding through which operate the upwardly-directed toothed projections 15 of a feeding element 16. This feeding element 16 may be of the four motion type, and, in its action, intermittently advances the work W leftward in Fig. 1 as it is being stitched on the support 10.

At 17 is shown the presser foot of the machine which, during the feeding, reacts upon the feeding element 16 in a well known manner. Arranged to cooperate with the needle 12 in stitch-formation below the work support 10 is a rotary hook which is comprehensively designated by the numeral 18, said hook having an axially hollow rotating component 19 whereof the rearwardly-projecting hub 20 is adjustably secured, by means of set screws 21, to the hook shaft 22, said component having a needle thread loop-seizing beak 23 and also a loop releasing horn 25. Disposed within the hollow of the rotating component 19 is a non-rotating component 26 which is likewise axially hollow and which has an interrupted circumferential rib 27 in engagement with an internal circumferential groove 28 in said rotating component. Housed in turn within the hollow of the non-rotating component is a bobbin case 29 which contains a thread bobbin 30, which latter is mounted for free rotation about an axial stud 31 within the bobbin case. Through engagement of a notch 32 at the top of the bobbin case 29 with a lug 33 internally of the component 26, said case is removably held in place with the aid of a retractable spring-influenced latch 35 which engages the stud 31. The thread B of the bobbin 30 emerges through an aperture 36 at one side 45 of the bobbin case 29 being drawn therefrom at a tangent in a direction opposite to that of hook rotation, and is subject to a finger spring 37 which imposes the necessary drag to tension the thread. Rotation of the hook structure is counterclockwise with its top moving in the direction of the feed stroke of the dog 16.

Except as about to be pointed out, the rotary hook is of the usual construction and cooperates in the customary way with the needle in stitch formation. Instead of being formed as ordinarily with two cheek projections at the top of its face flange 40, the non-rotating component 26 of the hook is provided, according to my invention, with but a single cheek projection 41, while the fixed 55 rotation-restraining element or finger designated

42 is formed with a recess 43 between two lateral inward projections 44 and 45 for engagement by said projection 41, the width of the recess being such as to afford sufficient clearance for the passage of the front limb of the needle thread loop as the latter sweeps across the face of the hook incident to stitch-formation. The finger 42 may be secured to the frame (not shown) of the sewing machine in any approved manner. It is to be noted from Fig. 1 that the cheek projection 41 is inclined somewhat to the vertical and, from Fig. 2, that said cheek is bevelled at the outer side to facilitate passage of the outer limb of the needle thread over it from left to right in the drawing. By the frictional action of the rotating component 19 of the hook upon the non-rotating component 26, it will be seen from Fig. 1 that the projection 41 is at all times yieldingly urged toward the projection 44. It is to be further remarked that the inner side of the cheek projection is longitudinally recessed for the provision of a groove 46 through which the bobbin thread reeves in its upward passage from the egress aperture 36 in the bobbin case 29 to the previously formed stitch in the work W. Consequently, during the interval incident to stitch formation when the work is being advanced leftward as shown in Fig. 1 by the action of the feeding element 16 with attendant pull on the bobbin thread B engaged in the notch 46 of the cheek projection 41, said cheek projection is maintained in contact with the lug 44 of the rotation-restraining element 42. In this way it will be seen that the free rotative play normally of the component 26, is effectively prevented to the exclusion of any counterrotation and slapping of said component as occurs in the operation of rotary hooks of ordinary construction.

The groove 45 in the cheek projection also performs another function, to wit, that of controlling the bobbin thread B and keeping it retracted out of rubbing contact with the front limb of the needle thread loop L as said limb traverses said cheek projection in its sweep across the hook face. This feature of my invention is of great advantage, not only in that it eases the movement of the needle thread loop around the body of the bobbin housing component 26, but in that it obviates thread rupture. It therefore follows that a sewing machine fitted with my improved rotary hook can be safely operated at higher speeds than ordinarily, and that finer as well as cheaper threads can be used in it without danger of breakage.

The plane smooth surface left on the face of the flange 40 of the bobbin housing component resulting from the omission of the usual right-hand cheek projection as at 47, also favors freer passage of the needle thread loop around said component.

Having thus described my invention, I claim:

1. Rotary hook mechanism to cooperate with the reciprocating thread carrying needle and feed mechanism of a lock stitch sewing machine, comprising a rotary needle thread manipulating component; a frictionally engaged non-rotating bobbin thread component from a point at the periphery of which the bobbin thread is drawn in a direction opposite to the direction of rotation of the thread manipulating component; and rotation restraining means for the non-rotating compo-

nent including a projection thereon, and a fixed element with a recess into which the projection loosely fits, said projection being maintained against that side of the recess which is forward in the direction of hook rotation by the frictional influence of the rotating component upon the non-rotating component and the pull on the bobbin thread, for maintenance of a substantially constant interval between said projection and the other side of the recess for free passage of the needle thread as the stitch is being set at the completion of each stitch forming cycle.

2. Rotary hook mechanism according to claim 1, in which the projection on the non-rotating component is notched to hold that portion of the bobbin thread which extends from the bobbin to a previously formed stitch in the work, so that said thread is held clear of the front limb of the needle thread loop as the latter sweeps across the face of said non-rotating component.

3. Rotary hook mechanism to cooperate with the reciprocating thread carrying needle and feed mechanism of a lock stitch sewing machine in which the work is intermittently advanced, comprising a non-rotating bobbin thread carrying component from a point at the periphery of which the bobbin thread is drawn in a direction opposite to the direction of rotation of the thread manipulating component; a rotating needle thread manipulating component revolving about said non-rotating component; and rotation restraining means for the non-rotating component including a fixed element with a recess, and a projection on said non-rotating component loosely fitting in said recess, said projection being contacted by that portion of the bobbin thread which extends from the bobbin to a previously formed stitch in the work, whereby, through pull on said thread as the work feeding takes place at the completion of each stitch forming cycle when the stitch is being set, the non-rotating component is slightly shifted rotatively and the projection thereon is thereby urged against the advance shoulder of the recess, for maintenance of a substantially constant interval between said projection and the other side of said recess for free passage of the needle thread.

4. Rotary hook mechanism to cooperate with the needle of a lock stitch sewing machine, comprising a rotary thread manipulating component; a non-rotating bobbin thread supply carrying component journaled in the rotary component; a rotation restraining member with a notch into which a projection on the non-rotating component extends, said projection being narrower than the notch, and, through rotation of the needle thread manipulating component caused to contact the stop shoulder at one end of the notch with maintenance of a clearance interval between it and the stop shoulder at the other end of the notch through which the needle thread loops can freely pass incident to release for stitch setting; and a guide provided in the projection through which the bobbin thread is drawn in a direction contrary to the direction of rotation of the rotary component so as to assist in keeping said projection in engagement with the first mentioned of the two stop shoulders of the rotation restraining member.

EMIL J. BILLINGTON.
